SAFETY RAZOR

Filed July 16, 1928

INVENTOR

John T. Scully

UNITED STATES PATENT OFFICE

JOHN T. SCULLY, OF NEW YORK, N. Y.

SAFETY RAZOR

Application filed July 16, 1928. Serial No. 293,064.

This invention relates to improvements in safety razors and has especial reference to guard sections in razors using interchangeable blades, an object being to provide a 5 guard section quickly and easily cleaned.

A further object of the invention is the provision of a guard section having a handle secured thereto in such manner as to permit a blade to be removed without removing the 10 handle from the guard.

A further object of the invention is the provision in a safety razor of a guard section capable of changing the cutting angle of a flexible blade.

15 Other objects will hereinafter appear.

In the drawings:—

Fig. 1 is an end view of the invention.

Fig. 2 is an end view in section taken along the line 2—2 of Figure 3.

20 Fig. 3 is a side elevation.

Fig. 4 is a top view.

Fig. 5 is a side view in section taken along the line 5—5 of Figure 1.

In my co-pending application Serial number 95,091, I have disclosed, with an uncovered blade section, a guard section having outwardly and oppositely extending guard edges (see Figs. 8 and 10 in above referred to application) and which guard edges form

25 the terminating sides or ends of a guard section having a longitudinally extending middle body portion to assist in holding the blade and having transversely and oppositely disposed sides leading therefrom to act as guard edges.

30 These sides lead downwards from the longitudinally extending middle body portion, then outwards, upwards and finally terminate in a direction substantially confronting the middle body portion.

35 In this invention a present purpose is to adapt this principle to safety razors employing blades of the so called wafer type.

Referring now to the drawings in detail, wherein like characters of reference denote 40 corresponding parts, a blade 4 is supported by a guard section 1, and held in position thereto by the clamping cap 3 which carries a post or stud 8 with threads thereon to engage a handle 5. The threaded post or 45 stud 8 passes through an aperture provided

in the blade 4 and engages threads provided in the handle head 10. Through the guard section 1 is an aperture 14 through which the handle 5 passes to engage the stud 8. On the clamping cap 3 are preferably provided 55 additional studs 12 and 12a, unthreaded, and aligned to fit in wells 13 provided in the guard section. The guard section 1 is provided with a longitudinally extending middle portion 6 from which transversely extend guard edges 2 and 2a in outwardly and opposite directions. The guard edges 2 and 2a are preferably constructed to form a row of teeth, although they may be made with plain edges without teeth. 60

The longitudinal edges of the guard edges 2 and 2a of the guard section 1 are upwardly and inwardly disposed and substantially confront a plane substantially parallel to the cutting edges of the blade, and may or may 65 not extend even with the blade edges; that is the blade may or may not overhang the longitudinal edges. On the curved inclination of the guards and lying ahead of their free ends and ahead of the edge of the flexed 70 blade is a skin-depressing arc 2b which lies within the plane of the arc of the flexed blade through its cutting edges so that if the plane of the arc of the blade were projected it would pass outside the skin-depressing arc 2b. Between the middle portion 6 of the guard 75 1 and each of the guard edges 2 and 2a are longitudinal passages 15 and 15a formed in the guard section by disposing upwards or forwards towards the blade the 80 guard edges 2 and 2a. This feature has the advantages of permitting lather and hair to accumulate in the passages and at the same time making the device readily cleanable by passing water through it. The cutting edge 85 of the blade 4 terminates perpendicularly above the free ends of the guard and extends lengthwise therewith; also, the cutting edge terminates preferably behind the guard's 90 free end skin-depressing surface 2b. 95

I also provide a handle 5 swivelled to the guard section by means of the securing member 9 in the aperture 14. The head of the securing member is internally threaded to engage the stud 8. The securing member has 100

a collar portion 10 spaced apart from the handle head 16 by the portion 9 which is of smaller circumference than the collar. The lower end of the collar 10 rests on a stop provided in the guard section 1, and the handle 5 where it joins the section 9 also meets a stop. The purpose of the stops is to substantially prevent, or at least limit, longitudinal motion while permitting rotation.

10 By turning the handle 5 the flexure of the blade can be controlled, or in case of non-flexible blades the guard edge spacing can be controlled. Also, the blade may be removed without detaching the handle from the guard 15 section thereby reducing the number of parts to handle.

In Figures 2 and 5 I show the manner in which the handle is assembled. A well 11 is provided in the handle 5. The end 16 is placed in alignment with the aperture 14 20 at the lower end while the section 9 of the handle securing member is aligned with the upper end of the aperture 14 and then driven through the aperture into the well 11.

25 I desire to point out that among the advantages of the curved guards as herein shown, an important purpose is to provide a smooth and substantially continuous "lead" for the guard, and I, also, desire to point out 30 that my handle and securing member construction are easily assembled and disassembled.

While I have shown a double edge blade and a double guard edge guard section, I wish 35 it to be understood that I hold a guard edge for one blade cutting edge to come within the scope of this invention, and that this invention has especial application to safety razors which include blade holding means whereby 40 the blade is held in position to a guard edge by blade holding means engaging the blade on more than one side thereof.

The invention is susceptible to many variations in its form, proportions and minor 45 details of construction, and the right is here- 50 in reserved to make such changes as properly fall within the scope of the invention.

Having described my invention what I claim is:—

55 1. In a safety razor, a blade-clamping member, a blade-supporting member, and a handle secured to the blade-supporting member by swivel means, said swivel means including a longitudinally extending well provided in the handle and engaging a longitudinally extending stud having a shoulder on the clamping member-confronting end.

60 2. A safety razor comprising a transversely-flexible blade having a longitudinal cutting edge, in combination with a blade holder having a blade-supporting member head, a guard formed on a curved inclination and having a free end spaced from said head, a skin-depressing surface included in said 65 curved inclination and lying ahead of said

free end, said skin-depressing surface shaped ahead of the free end to curve within the plane of the projected plane through the cutting edge of the blade when flexed, a longitudinally extending lather-catching passage 70 outwardly defined by the curved inclination, means for positioning the blade on said blade-supporting member head, a blade-clamping member overhanging the blade contacting face of the head and shaped to flex the blade 75 transversely, and means for forcing the parts together with the cutting edge of the blade extending lengthwise with and spaced perpendicularly above the said free end of the guard, said forcing means including a handle swivelled to the blade-supporting member.

3. In a safety razor, a blade holder including the combination of a blade-supporting member of one piece construction provided 85 on its upper side with a blade contacting head and on its lower side with an outwardly extending portion formed to a curved inclination to provide guard fingers having their free ends spaced from said head, a skin-depressing surface included in said curved 90 inclination and lying ahead of said free ends, said skin-depressing surface shaped ahead of the free ends to curve within the plane of the projected plane through the 95 cutting edge of the blade when the latter is flexed, a longitudinally extending lather-catching passage outwardly defined by the said curved inclination, means for positioning a transversely flexible blade on said head, 100 a blade-clamping member overhanging the blade contacting head and shaped to flex the blade transversely, and means for adjustably forcing the parts together with the cutting edge of the blade extending lengthwise 105 with and spaced perpendicularly above the free ends of the guard fingers, said forcing means including a handle secured to the blade-supporting member by swivel means comprising a longitudinally extending well 110 in the handle in engagement with a longitudinally extending internally threaded stud having a shoulder seated in an annular recess provided in the blade-supporting member.

115 In testimony whereof I, JOHN T. SCULLY, hereunto affix my signature.

JOHN T. SCULLY.
